UNITED STATES PATENT OFFICE.

GEORGE W. COMBS, OF LEAVENWORTH, KANSAS.

GYRATORY STRUCTURE.

1,071,706.

Specification of Letters Patent.

Patented Sept. 2, 1913.

Application filed May 5, 1908. Serial No. 430,989.

To all whom it may concern:

Be it known that I, GEORGE W. COMBS, citizen of the United States, residing at Leavenworth, in the county of Leavenworth and State of Kansas, have invented certain new and useful Improvements in Gyratory Structures, of which the following is a specification.

My invention relates to improvements in gyratory structures such as flour-sifters, &c.; and the invention embraces a novel shaft or shafts for driving the structure and a weight or weights for unbalancing the structure when in motion so that it will gyrate. The weight may be rigidly secured to the shaft, but I prefer to pivot it thereto so that said weight may automatically adjust itself to the different speeds of the structure and thereby prevent the latter from bucking or leaving its true gyratory course while starting or stopping, or after its shaft has attained its critical speed of rotation.

My principal object is to overcome the serious defect which heretofore arose in structures employing weights to impart a gyratory motion thereto. This defect is caused by the weights pulling one side of the drive-shaft against its bearings, with the result that said side is worn flat and the interior of the bearings is worn larger than the shaft, so that the latter is free to move laterally or vibrate in the former greatly to the detriment of both. I do not overcome wear of the shaft or its bearings, but I do construct and arrange the parts so that the greater portion of the wear occurs at one side of the bearings, and as said side is constantly held in contact with the stationary section of my improved shaft by the weights, independent movement between the shaft and its bearings, and the detrimental results arising therefrom, is obviated.

In the accompanying drawings illustrating the invention:

Figure 1 represents a vertical central section of a gyratory structure provided with the preferred form of my improvements. Fig. 2 is a plan view of the gyratory structure, provided with a modified form of my improvements. Fig. 3 is a side elevation of the same. Fig. 4 is an enlarged vertical section on line IV-IV of Fig. 2. Fig. 5

is a detail cross section on line V-V of 55 Fig. 1.

1 designates the gyratory structure which in the present instance consists of a pair of oppositely-disposed sieve-boxes 2, united by a plurality of bridge-trees 3, provided with 60 bearings 4. The sieve-boxes are supported by flexible rods 5 so they may freely gyrate.

6 designates a pair of vertically-positioned shafts for driving the structure, which are arranged, preferably, midway between the sieve-boxes. Each shaft consists of a stationary section 7, fixed in bearings 4, and a tubular section 8 journaled upon section 7 and extending, preferably, almost the entire length thereof. Section 8 is provided 70 with a pair of boxes 9 which are journaled on section 7 and secured to section 8 by set-screws 10, so they may be removed and rebabbitted when necessary. Sections 8 rest upon ball-bearings 11 in the lowermost 75 bearings 4, so their operation will be attended with but little friction.

12 designates two bevel gear wheels fixed to sections 8 and intermeshing with bevel gear wheels 13 mounted upon a horizontal 80 shaft 14, provided with a centrally-disposed driver 15 fixed thereon. Shaft 14 is journaled in a pair of bearings 16 carried by the uppermost bridge-trees so that the bevel gear wheels, shaft 14, and driver 15 may 85 swing or gyrate with the structure.

Bearings 16 are provided with lubricant chambers 17 and ducts 18, which latter extend through the bottom of the bearings and communicate with the uppermost bearings 4, so that a portion of the lubricant may flow therein and follow sections 7 of the shafts downward to the lowermost bearings 4, thus bearings 4, boxes 9, and the ball-bearings 11, will be freely supplied 95 with oil. The oil is prevented from overflowing from the lowermost bearings 4 by packing 19 and glands 20, which latter are adjustably secured to the bearings by screws 21.

A gyratory motion is imparted to the structure when the shafts are rotated, by a pair of centrifugally-controlled unbalancing members consisting of weights 22, pivotally secured to sections 8 by transverse 105 pins 23 so they may swing upwardly to a horizontal position as the speed of the structure increases. Sections 8 are reinforced

100

by longitudinal ribs 8^a which receive the pins 23 and prevent the sections from springing inward at their central portions beneath the weight exerted thereon by the 5 unbalancing members.

Members 22 are, preferably, secured to sections 8 midway between the ends of the same so that when said members swing upward to a horizontal position they will more 10 evenly balance the structure and prevent it from rolling, or in other words, prevent the top of the structure from describing a greater or less circle than its bottom portion. The free ends of the members 22 are 15 provided with pockets 24 for the reception of additional weights when it is necessary to employ the latter, and they also have recesses 25 so the members may swing downward in line with the drive-shafts when at 20 rest, see dotted lines on Fig. 4.

In operation it is obvious that the centrifugal force of the drive-shafts will cause the unbalancing members 22 to swing upward in proportion to the speed of said shafts, 25 and as they swing upward and outward they will have a tendency to pull sections 8 therewith and, consequently, cause boxes 9 to wear on the side opposite the free ends of the unbalancing members, while the stationary 30 sections 7 will be worn evenly around their circumference by the boxes rotating thereon. Sections 7 and 8, however, will be prevented from having independent lateral movement because the rotating unbalancing members will always hold the snugly fitting 35 worn side of boxes 9 in contact with the stationary sections 7 as shown in Fig. 5, whereas if ordinary shafts, journaled in stationary boxes, were employed said shafts would be 40 worn flat on the side adjacent the free ends of the unbalancing members and the bore of the boxes would be worn much larger than the shafts, so that the same would be free to move laterally therein, greatly to the 45 detriment of both, as it is obvious that the shafts would pound against the boxes while rotating.

In the modified form shown by Figs. 2 to 4, inclusive, the mechanism is substantially 50 a duplicate of that shown in Fig. 1, with the exception that the stationary sections of the drive-shafts do not extend entirely through the tubular sections. Referring now in detail to said modified form, 1^a designates the gyratory structure, which consists of a pair of oppositely-disposed sieve-boxes 2^a united by bridge-trees 3^a and freely supported by flexible rods 5^a. 6^a designates a pair of drive-shafts mounted in the structure. Each shaft consists of a stationary section 7^a, integral with the upper bridge-tree, and a rotary section consisting of a tubular member 8^b and a solid section 8^c secured together by a set-screw 26. Section 65 8^c is journaled at its lower end in a bearing

4^a secured to the lowermost bridge-tree. Section 8^b is provided with a box 9^a which is journaled on section 7^a and pivotally mounted upon a pair of oppositely-disposed set-screws 10^a, so that it will not bind upon section 7^a should it get out of alinement with section 8^b, and so that it may be removed and rebabbitted when necessary: Sections 8^b, like sections 8 form lubricant chambers for the reception of a supply of oil for the boxes and the stationary sections of the shafts. Sections 8^c are provided near their lower ends with bevel gear wheels 12^a which intermesh with a pair of bevel gear wheels 13^a fixed upon a shaft 14^a journaled in bearings 16^a and provided with a driver 15^a. 22^a designates a pair of unbalancing members which are duplicates of members 22 and are pivotally secured to sections 8^b of the drive-shafts by pins 23^a.

While I have shown two drive-shafts for each structure, one centrally-disposed shaft is sufficient for small structures, hence I do not limit myself to the exact construction shown but reserve the right to make such changes as properly fall within the spirit and scope of the appended claims.

Having thus described my invention, what I claim is:—

1. In combination, a gyratory structure, a drive-shaft therefor consisting of a stationary section fixed to and carried by the structure and a rotary section journaled on the stationary section and supported by the structure, and an unbalancing member connected to the rotary section of said drive-shaft.

2. In combination, a gyratory body, means for freely supporting said body, a drive-shaft therefor consisting of a stationary section fixed to and carried by the body and a rotary section journaled on the stationary section and resting on the body, and an unbalancing member connected to the rotary section of said drive-shaft.

3. In combination, a gyratory structure, supporting means for said structure preventing rotation thereof, a drive-shaft therefor consisting of a stationary section fixed to and carried by the structure and a rotary section journaled on the stationary section and resting on the structure, and an unbalancing member connected to the rotary section of said drive-shaft.

4. In combination, a gyratory box, a shaft supported thereby consisting of a stationary section and a rotary section journaled on the stationary section and resting on the box, a driver for the shaft also supported by said box, and an unbalancing member connected to the shaft.

5. In combination, a suspended body, a shaft arranged therein and weighted to produce a gyratory movement, said shaft consisting of a stationary section fixed to and

- carried by the suspended body and a rotary section journaled on the stationary section and supported by the suspended body, and a swinging driver for said shaft.
- 5 6. In combination, a gyratory structure consisting of one or more boxes, a vertically-positioned drive-shaft for said structure, consisting of a stationary section fixed to and carried by the structure and a rotary section 10 journaled on the stationary section and supported by the structure, and an unbalancing weight connected to said shaft.
- 15 7. In combination, a suspended body, shafts therefor consisting of stationary sections fixed to and carried by the suspended body and rotary sections journaled on the stationary sections and supported by the suspended body, weights mounted on said shafts whereby they are given a tendency when in motion to travel in a gyratory path, a driver 20 carried by the suspended body and adapted to swing or gyrate therewith, and gearing for imparting motion from said driver to the shafts.
- 25 8. In combination, a freely-supported structure, bridge-trees forming a part thereof, a drive-shaft for said structure and consisting of a stationary section fixed to and carried by said bridge-trees and a rotary 30 section journaled on the stationary section and supported by the bridge-trees, and an unbalancing member connected to said drive-shaft.
- 35 9. In combination, a gyratory structure, a plurality of drive-shafts therefor consisting of stationary sections fixed to and carried by said structure and rotary sections journaled upon the stationary sections and supported by the structure, a centrally-disposed 40 driver for driving the rotary sections, and pivoted unbalancing members mounted on said rotary sections.
- 45 10. In combination, a gyratory structure, a stationary drive-shaft section fixed to and carried by the structure, a tubular drive-shaft section embracing the stationary section and supported by the structure, bearings removably secured in the tubular section and journaled upon the stationary section, and an 50 unbalancing member mounted on said tubular section.
- 55 11. In combination, a pair of oppositely-disposed boxes, a pair of shafts spaced apart and mounted midway between said boxes for driving the same, centrifugally-controlled unbalancing members pivoted to the shafts about midway between the ends of the same,
- and a driver mounted independently of said shafts but geared thereto to drive the same.
12. In combination, a suspended structure, 60 a stationary drive-shaft section fixed to and supported by the structure, a tubular drive-shaft section journaled on the stationary section and forming a lubricant-chamber for the reception of oil for both the stationary 65 and rotary sections, said rotary sections being supported by the structure, and an unbalancing member secured to the tubular section.
13. In combination, a structure freely sus- 70 pended for gyration, two pairs of bridge-trees secured to the ends of said structure, a vertical shaft carried by each pair of bridge-trees, a driven horizontal shaft journaled in one of each pair of bridge-trees, a bevel gear 75 wheel on one end of each vertical shaft, and bevel gear wheels on the ends of the horizontal shaft for driving the bevel gear wheels on the vertical shaft.
14. In combination, a structure freely sus- 80 pended for gyration, two pairs of bridge-trees secured to the ends of said structure, a vertical shaft carried by each pair of bridge-trees, a driven horizontal shaft journaled in one of each pair of bridge-trees, a bevel gear 85 wheel on one end of each vertical shaft, bevel gear wheels on the ends of the horizontal shaft for driving the bevel gear wheels on the vertical shaft, and unbalanc- 90 ing weights on the vertical shaft.
15. In combination, a gyratory structure, a plurality of drive-shafts therefor, each of which consists of a stationary section extending nearly through the structure and carried thereby and a rotary section journaled on the stationary section and resting on the structure, unbalancing members connected to the rotary sections of the drive-shafts, and a driver geared to said rotary sections.
- 100 16. In combination, a suspended structure, a vertical stationary drive-shaft section fixed to and supported by the structure, a tubular drive-shaft section journaled on the stationary section and forming a lubricant-chamber, and means carried by the structure at the lower end of the lubricant-chamber to prevent leakage of oil from the same.

In testimony whereof I affix my signature, in the presence of two witnesses.

GEORGE W. COMBS.
